Alvanda S. Janit.
His Attorney.

UNITED STATES PATENT OFFICE.

GLENN B. WARREN, OF SCHENECTADY, NEW YORK, ASSIGNOR TO GENERAL ELECTRIC COMPANY, A CORPORATION OF NEW YORK.

ELASTIC-FLUID TURBINE.

Original application filed December 22, 1923, Serial No. 682,325. Divided and this application filed July 21, 1924. Serial No. 727,149.

To all whom it may concern:

Be it known that I, GLENN B. WARREN, a citizen of the United States, residing at Schenectady, in the county of Schenectady, State of New York, have invented certain new and useful Improvements in Elastic-Fluid Turbines, of which the following is a specification.

This application is a division of my application Ser. No. 682,325, filed December 22, 1923.

In building high speed, large capacity turbines, the buckets in the last few stages become quite long which means that there is considerable difference in peripheral speed between the roots of the buckets and their tips. The result is that if in an impulse turbine the central portions of the buckets are running at a speed correct for most efficiently extracting the energy from the elastic fluid issuing from the nozzle then the root portions are running too slow for highest efficiency and the tip portions are running too fast for highest efficiency.

The object of my invention is to provide an improved means for overcoming this difficulty due to the difference in speed between the roots and the tips of long buckets whereby better efficiency will be obtained.

In the design of elastic fluid turbines, it has been found that in order to absorb the same quantity of energy from an elastic fluid a pure reaction combination of nozzle and bucket must run at a speed about 40% greater than a corresponding impulse combination. This means that if the root end of a bucket is running at about the right speed to operate as an impulse bucket, the tip end would be running at a speed adapted for either total or partial reaction operation.

In carrying out my invention, I take advantage of this fact, and according to my invention in the case of long buckets I so shape the buckets that the fluid passages of the nozzle-bucket combination operate as an impulse combination at their inner or root ends and as either a partial or total reaction combination at their outer or tip ends. According to the embodiment of the invention illustrated in this application, the above referred to result is accomplished by so constructing the buckets as to give a smaller

exit angle at the radially outer ends or tips of the buckets than at their radially inner ends or roots.

In the drawing Fig. 1 is a radial sectional view through a nozzle-bucket combination embodying my invention and Figs. 2 and 3 are sectional views taken on lines 2-2 and 3-3 respectively in Fig. 1.

Referring to the drawing, 1 indicates a turbine shaft carrying rotor elements 2 and 3 on which are the bucket rows 4 and 5, and 6 indicates the turbine casing carrying the stationary fluid directing nozzles 7. Only a fragment of the turbine is shown, the portion illustrated being adjacent stages at the low pressure end of the machine. In the present instance, the nozzles are formed in a diaphragm 8, the nozzle partitions being indicated at 9. The nozzles receive elastic fluid from bucket row 4 and deliver it to bucket row 5. The construction of the buckets of the nozzle-bucket combination comprising nozzles 7 and buckets 5 is such that the radially inner portion of the combination operates as an impulse combination and changes toward the radially outer portion until at the outer portion the combination operates partially or wholly as a reaction combination the change being gradual from the one to the other. This is accomplished by varying the exit angle of the buckets from their inner ends to their outer ends, the inner ends having an exit angle b as indicated in Fig. 2 and the outer ends having an exit angle b minus an amount y , as shown in Fig. 3. The nozzle angle a is shown as remaining constant.

Since the outer ends of the buckets have a certain amount of reaction there is of course, some drop in pressure across them and to limit the leakage I provide suitable packing means as indicated at 10. At 11 is indicated the usual diaphragm packing.

By my invention I provide a nozzle-bucket combination which takes care of the difference in speed between the roots and the tips of the buckets and thereby gives better efficiency for the combination than has been obtained heretofore. It will be understood that I am using the term nozzle in a broad sense and intend to include thereby any stationary fluid directing element.

What I claim as new and desire to secure by Letters Patent of the United States, is:—

In an elastic fluid turbine, a nozzle-bucket combination wherein the exit angle of the buckets decreases from the roots of the buckets to their tips by an amount such that the combination changes from impulse operation at the radially inner portion to at least

partial reaction at the outer portion, the change being made commensurate with the difference in speed at which the radially inner and outer portions of the buckets rotate.

In witness whereof, I have hereunto set my hand this 18th day of July, 1924.

GLENN B. WARREN.
